EDWIN FREUND, OF VIENNA, AUSTRIA

SQUEEZING MACHINE

Application filed December 12, 1928, Serial No. 325,434, and in Austria December 14, 1927.

This invention relates to improvements in machines for dyeing, impregnating, kneading, and mixing or intimately and evenly compounding by the process of alternately turning and squeezing the materials to be treated.

The machine comprises a vessel, preferably with two sides parallel to each other, a rocking shaft placed at right angles to them, a vane worked by the said rocking shaft alternately towards and away from a plate which stands also at right angles to the said sides of the vessel and is called the butt; a narrow, essentially horizontal ledge at the bottom 15 of the butt and on that side of it which faces the vane and a bottom forming a continuation of the ledge but shaped in accordance with the path swept by the bottom edge of the vane, preferably in such a way that the 20 gap between the bottom edge of the vane and the bottom widens as the vane moves nearer to the butt.

The vane, the bottom and the butt are advantageously made of screen-like materials 25 easily pervadable by liquids.

The faces of the sides of the vane and of its bottom edge are, with advantage, bent forward a little in order to move the material to be treated away from the gaps at 30 the sides of the vane and below, so as not to be caught between vane and sides of the vessel, or vane and bottom.

These forward bent portions and the adjoining ones are free from projections, such 35 as for instance corrugations which would interfere with the scavenging action of the forward bent wings and bottom lip of the vane.

The action of the machine will be fully 40 understood by referring to the drawings, wherein Figure 1 is a vertical section of the machine, and Figure 2 is a top plan view thereof.

The parts are indicated by the following 45 numbers: The vessel with 1; the covers of the charging ports with 2, said covers being shown in full and dotted lines in Figure 1; a pan for placing the goods in after treatment with 3, said pan forming a loose cover for 50 the center of the vessel 1. The two bottoms

are indicated by the numerals 4 and 5; the butts by 6 and 7; the ledges by 8 and 9; the rocking shaft by 10; the vanes by 11, said vanes having forward bent wings 12, 13, 14 and 15; and bent bottom lips 16 and 17. The 55 rocking shaft has a crank 18 and a counter-shaft 19 is also provided which has a crank 20. Cranks 18 and 20 are joined by a connecting rod 21. The bundles of material treated between the vanes and the butts of the machine are indicated by 22 and 23 and the numerals 24 and 25 represent the bearings of the rocking shaft. The vanes 11 are fixed on arms 26 and 27.

The bundles 22 and 23 of material, such 60 as linen to be washed in the machine, are inserted between the vane and butts and are, on the forward stroke of the (left-hand side) vane 11 towards the butt 6, squeezed against this butt and formed into a lump of prismatic 65 shape like the bundle 22 between the right-hand side vane 11 and butt 7 which rests on ledge 9.

When the vane recedes from the position 70 shown, bundle 22 is by adhesion retained on butt 7, but as the vane proceeds on its return stroke said bundle topples over the left-hand side edge of the ledge 9 into the position in which bundle 23 is shown. On the next forward stroke the left-hand side vane 75 11 strikes first that side of the bundle 23 which was originally on top and pushes the same up the bottom 4 until it touches butt 6 and squeezes it then into a new lump of similar shape as before. While the vane is away 80 from the butt the bundle has time to get well soaked with suds with which the vessel is filled up to the proper level. During the return stroke of the vane the suds and any matter 85 that has been dissolved by it is squeezed out again and portions of the cloth are shoved past each other, rubbing off soft matter adhering. When this action has been repeated a certain number of times all dissolvable matter 90 has been passed into the suds.

The efficiency of the machine is considerably increased by perforating the supporting 95 surfaces of the bottoms 4 and 5, the butts 6 and 7, and the vanes 11, so that soiled liquid is quickly carried away through said bottoms 100

and a more thorough circulation of the liquid effected through the butts and vanes. To this end, the central portions of the vanes 11 are provided with perforations 28, while the 5 wings 12 and 13 are formed with the perforations 30. Similar perforations 31 and 32 are provided in the bottoms 4 and 5 and the butts 6 and 7, respectively.

It will be seen from Figure 1 that the lips 10 or faces 16 and 17 of the bottom portions of the vanes 11 each form an acute angle with a plane extending through the bottom edge of the lip and the axis of the shaft 10, as indicated by the dot and dash line 33. Also, 15 the faces of the wings 12 and 13 form acute angles with a plane extending vertically and transversely through the shaft 10, said plane being indicated by the dot and dash line 35 in Figure 2 and the acute angles being designated by the numerals 36 and 37.

Dyeing processes are carried on in a similar way except that the coloring matter is carried into the material to be dyed.

What is claimed is:

25 1. A squeezing machine comprising a vessel, a rocking shaft, a vane movable to and fro by the said shaft, a butt facing the vane, a bottom shaped in accordance with the path swept by the said vane and an essentially horizontal ledge placed between the butt end of the bottom and the butt.

30 2. A squeezing machine comprising a vessel, a rocking shaft, a vane movable to and fro by the said shaft, a butt facing the vane, a bottom shaped in accordance with the path swept by the bottom edge of the vane, an essentially horizontal ledge placed between the butt end of the bottom and the butt, the vane in its foremost position including with the 35 butt and the ledge a wedge-shaped space, the center of gravity of which lies on the vane 40 side of a vertical plane passing through said ledge.

35 3. A squeezing machine comprising a vessel, a rocking shaft, a vane movable to and fro by the said shaft, a butt facing the vane, a bottom shaped in accordance with the path swept by the said vane, an essentially horizontal ledge placed between the butt end of the bottom and the butt, the face of the lower 50 part of the vane forming an acute angle with a plane extending through its bottom edge and through the axis of the rocking shaft.

40 4. A squeezing machine comprising a vessel, a rocking shaft, a vane having wings and being movable to and fro by the said shaft, a butt facing the vane, a bottom shaped in accordance with the path swept by the said vane, an essentially horizontal ledge placed 45 between the butt end of the bottom and the butt, the faces of the wings of the vane including acute angles with a plane extending vertically through the axis of the rocking shaft and situated between the wings of the 50 vane.

5. A squeezing machine comprising a vessel, a rocking shaft, a vane movable to and fro by the said shaft and having wings, a butt facing the vane, a bottom shaped in accordance with the path swept by the said vane, an essentially horizontal ledge placed 70 between the butt end of the bottom and the butt, the face of the bottom part of the vane forming an acute angle with a plane extending through its bottom edge and through the 75 axis of the rocking shaft, and the faces of the wings of the vane including acute angles with a plane extending vertically through the axis of the rocking shaft and situated between the wings of the vane.

6. A squeezing machine comprising a vessel, a rocking shaft, a vane movable to and fro by the said shaft, a butt facing the vane, a bottom shaped in accordance with the path swept by the said vane, an essentially horizontal ledge placed between the butt end of the bottom and the butt, and means to removably mount said butt in the vessel.

In testimony whereof I have signed my name to this specification.

EDWIN FREUND.
